UNITED STATES PATENT OFFICE

THEODORE RUSSELL, OF NAUGATUCK, CONNECTICUT

TONGUE BUCKLE AND PROCESS FOR MAKING SAME

Application filed June 10, 1930. Serial No. 460,166.

This invention relates to buckles, and more particularly to an improvement in a process of manufacturing pivoted tongue buckles, whereby the tongue of the buckle is produced directly from the metal of the buckle frame. 5

One object of this invention is to provide a process of producing buckles which will be simple in operation, economical of labor and material, and in which the buckle produced 10 will be ornamental in appearance, and efficient and durable in use.

With these and other objects in view there has been illustrated on the accompanying drawing one form in which the invention 15 may be conveniently embodied in practice.

In the drawing:

Fig. 1 represents a plan view of a metal strip showing the appearance of the buckle after the various successive steps of the process have taken place. 20

Fig. 2 is a side view of the same.

Referring now to the drawing in which like reference numerals denote corresponding parts throughout the several views, the 25 numeral 10 indicates the original flat metal strip from which the buckle is made, said strip being fed by suitable mechanism, not shown, through an automatic stamping and bending machine, not shown, from left to right as viewed in Figs. 1 and 2. The various successive steps of the process are adapted to be performed by a series of tools consisting of dies and plungers, not shown, between which said strip is moved intermittently. 30

The first step in the process consists of a piercing operation by means of which two metal pieces are stamped out leaving a pair of rectangular openings 11 and 12 in said strip. The longitudinal piece between said 40 openings 11 and 12 is partially pointed at the end 13, but not entirely severed from the frame.

The second step, which occurs after the strip has been moved through the machine a 45 distance equal to the length of the finished buckle frame 15, the ends of which are indicated by the dotted lines, consists in another piercing operation, leaving a rectangular aperture 14 in the right-hand end of the buckle frame. A pair of inwardly extending

cross-bar sections 16 and 17 are left at the center of the frame, and said sections 16 and 17 have reduced central portions 18 and 19 which are joined together by a longitudinal tongue section 20 having a free end 21 which is adapted to be later bent about the cross-bar of the buckle frame. It will be understood that the tongue is thus formed from material which is scrapped in the ordinary process of manufacturing buckle frames, and thereby results in a great saving of cost 55 thereover. 60

The third step consists in simultaneously bending the free end 21 of the tongue into a curved section 22 and a vertical heel 23, as most clearly shown in Fig. 2, and shearing the cross-bar sections 16 and 17 from the tongue section 20. 65

The fourth step in the process consists in pressing the free end of the tongue 20 downwardly out of the plane of the frame 15 and then closing in the initially straight sides 24 and 25 of the buckle frame to form inwardly curved side members 26 and 27, and causing the cross-bar sections 16 and 17 to be brought 70 into abutment to form a continuous cross-bar. 75

The fifth step, which occurs immediately after the squeezing-in of the cross-bar sections, consists in shearing the point 13 of the tongue from the left-hand end 28 of the buckle frame, after which the heel 23 of the tongue will be bent rearwardly and downwardly around the reduced sections 18 and 19 of the cross-bar into engagement with the base of said tongue at the point 29. This last operation is preferably accomplished with the aid of a stationary bumper not shown, located on the edge of the machine in the path of the tongue. 80 85 90

The sixth and last step of the process consists in shearing the left-hand end 28 of the buckle frame 15 away from the strip 10. The buckle is then completely formed and the process has been completed. 95

It will be understood that if desired, instead of forming the tongue in the manner above described, the tongue may be blanked out completely from the strip in the first operation, and the stamped-out tongue later 100

connected to the frame by bending its loop-end around the squeezed-in cross-bar sections, within the spirit and scope of the invention.

It will also be understood that the process 6 may be performed by hand as well as by machine as herein described.

While there has been disclosed in this specification one form in which the invention may be embodied, it is to be understood 10 that this form is shown for the purpose of illustration only, and that the invention is not to be limited to the specific disclosure but may be modified and embodied in various other forms without departing from its 16 spirit. In short, the invention includes all the modifications and embodiments coming within the scope of the following claims.

Having thus fully described the invention, 20 what is claimed as new, and for which it is desired to secure Letters Patent, is:

1. The process of making a buckle having a hinged tongue which comprises cutting end pieces out of a sheet metal frame to form 25 openings at both ends of said frame and leaving an integral transverse cross-bar at the center thereof and a longitudinal tongue joined to said cross-bar, severing said tongue from said cross-bar, forcing said tongue section below the plane of said frame, pressing the sides of said frame inwardly to cause said 30 cross-bar sections to come into abutment, and bending the end of said tongue around said cross-bar.

2. The process of making a buckle having 35 a hinged tongue connected to a cross-bar, which comprises stamping two pieces out of one end of a metal frame, leaving a tongue section therebetween, the end of which is still connected to said frame, stamping a single 40 piece out of the other end of said frame leaving a central tongue section having a free end, transverse cross-bar sections being formed at the center of said frame integral with said tongue sections, severing said cross- 45 bar sections from said tongue sections, bending said tongue about the end of the frame until its free end section is below the plane of said frame, pressing the sides of said frame inwardly to bring said cross-bar sections into abutment, and bending the free 50 end of the said tongue around said cross-bar.

3. The process of making a buckle having 55 a hinged tongue connected to a cross-bar, which comprises stamping two pieces out of one end of a metal frame leaving a tongue section therebetween, the end of which is still connected to said frame, stamping a single piece out of the other end of said frame 60 leaving a central tongue section having a free end, transverse cross-bar sections being formed at the center of said frame integral with said tongue sections, severing said cross-bar sections from said tongue sections, bending said tongue about the end of the 65

frame until its free end section is below the plane of said frame, pressing the sides of said frame inwardly to bring said cross-bar sections into abutment, severing the end of said tongue from the frame, and bending the other end of said tongue around said cross-bar. 70

4. The process of making a buckle having a hinged tongue connected to a cross-bar, which comprises stamping two pieces out of 75 one end of a metal frame leaving a tongue section therebetween, the end of which is still connected to said frame, stamping a single piece out of the other end of said frame leaving a central tongue section having a free end, transverse cross-bar sections being formed at the center of said frame having reduced inner extremities integral 80 with said tongue sections, severing said cross-bar sections from said tongue sections, bending said tongue about the end of the frame until its free end section is below the plane of said frame, pressing the sides of said frame inwardly to bring said cross-bar sections into abutment, and bending the free 85 end of said tongue around said cross-bar. 90

5. The process of making a hinged-tongue buckle from a single metal blank, which comprises stamping end pieces out of said blank leaving a pair of transverse cross-bar sections and a longitudinal tongue integral therewith, severing said tongue from said cross-bar sections, forcing the inner extremities of said cross-bar sections into abutment, and looping one end of said tongue around the abutted ends of said cross-bar sections. 100

6. The process of making a hinged-tongue buckle from a single metal blank, which comprises stamping a tongue from the longitudinal central section of said blank leaving a pair of spaced transverse cross-bar sections, forcing said cross-bar sections inwardly into abutment, and looping one end of said tongue around the abutted ends of said cross-bar sections. 110

7. The process of making a hinged tongue buckle, which comprises cutting out metal from the end sections of a sheet metal blank to produce an intermediate transversely extending member integral with said blank, and a longitudinal tongue member having one end integral with said blank, looping the other end of said tongue member around said intermediate member, and detaching said tongue member from said blank. 115

8. In a buckle, a sheet metal frame having openings at both ends with a pair of intermediate transverse cross bar members extending inwardly from the sides of said frame, a sheet metal tongue, the sides of said frame being bent inwardly to bring said cross bar members into abutment, one end of said tongue being looped around the abutting sections of said members. 120

9. In a buckle, a sheet metal frame hav- 125

ing interior openings near both ends leaving an intermediate transverse cross bar member, a tongue having one end bent around said cross bar, the sides of said frame being forced inwardly, the width of said tongue being approximately equal to the distance said sides have been forced in.

5 In testimony whereof, I have affixed my signature to this specification.

THEODORE RUSSELL.
